5 Claims. (Cl. 336—197)

ABSTRACT OF THE DISCLOSURE

A transformer comprising a magnetic core having leg and yoke portions, concentric windings surrounding a leg portion of the core, and a laminated metallic pressure ring positioned between the ends of said windings and the yoke portions of said core, said pressure ring comprising a plurality of concentric turn laminations, and means applying pressure to said pressure rings to maintain said windings under pressure.

This invention relates to core-form transformers having high reactance and high leakage flux, and particularly to an improved core-form transformer incorporating improved metallic pressure plates or rings.

In core-form transformers of the prior-art concentric high voltage and low voltage windings, with the low voltage windings inside of the high voltage windings, are plated about the legs of the magnetic core. A frame member is usually attached to the upper and lower yoke portions of the magnetic core. A metallic pressure plate or ring is usually placed against the concentric coils of windings at both ends of the concentric coils or windings. Jack-screws are attached to the frames, which are attached to the upper and lower yoke members. These jack-screws are tightened down against the metallic pressure plates or rings to maintain the concentric coils or windings under pressure to prevent movement of the coils or windings under short circuit conditions. The pressure plates or rings are usually made of steel and are from one-half inch to an inch or more in thickness and are washer shaped and have about the same inside and outside diameter as the concentric coils or windings to which they are applied.

These prior-art steel pressure plates or rings have several disadvantages. These prior-art pressure plates or rings are usually made by flame cutting from solid steel plate. In this process of providing the pressure plates or rings, sharp points exist on the edges of the plates or rings and these sharp points serve as points for starting corona and electrical breakdown. In transformers having high reactance and high leakage flux eddy currents are set-up in the solid steel pressure plates or rings and these eddy currents cause increased losses. These eddy currents also cause the solid pressure plates or rings to heat up to a temperature high enough in some cases to cause the adjacent cellulosic insulation to become scorched or burned. When the cellulosic insulation becomes scorched or burned its insulation value deteriorates and this could cause the transformer to fail.

It is a principal object of this invention to provide an improved core-form transformer wherein the above referred to disadvantages of the prior art transformers are eliminated.

It is a further object of this invention to provide an improved core-form transformer wherein laminated metallic pressure plates are provided between the ends of the coils and the core.

These and other objects of this invention will be ap-

2

parent from the following description taken in connection with the accompanying drawings, in which:

FIGURE 1 is a partial perspective view of a core-form transformer incorporating laminated pressure plates as provided by this invention;

FIG. 2 is a partial sectional view through one set of the concentric coils or windings shown in FIG. 1;

FIG. 3 is a plan view of the new laminated metallic pressure plate or ring of this invention; and

FIG. 4 is a sectional view taken along the line IV—IV of FIG. 3.

Like reference characters indicate like elements throughout the description which follows, unless otherwise indicated.

Referring to the drawing in detail, FIG. 1 is a core-form transformer having high reactance and high leakage flux which utilizes laminated metallic pressure plates or rings. The transformer of FIG. 1 comprises a magnetic core 10 having three leg portions 12, 14 and 16, with an upper yoke portion 18 and a lower yoke portion 19 connecting the three leg portions to provide a closed magnetic circuit. The leg portions and the yoke portions of the core are made up by stacking laminations of grain oriented silicon steel having at least one preferred direction of grain structure.

A coil or winding 20 comprising a low voltage section 21 and a high voltage section 23 is placed on each of the core legs 12, 14 and 16 before the upper yoke portion 18 is placed in position. A pressure ring or plate 22 is placed adjacent the lower end and adjacent the upper end of each of the coils or windings 20 during the assembly of the transformer. Frame members 24 and 26 are clamped to the upper yoke member 18 and to the lower yoke member 19 by means of bolts 28. The frame members 26 and 28 are provided with jack-bolts 30. The jack-bolts 30 are positioned in such a manner that after the coils 20 and the pressure plates or rings 22 have been assembled in position on the legs of the core 10, the jack-bolts 30 are adjusted to apply pressure to the upper and lower pressure plates or rings 22 to prevent the concentric coils or windings 21 and 23 from moving under short circuit conditions.

The jack-bolts 30 are positioned in such a manner that at least four jack-bolts 30 apply pressure to both the upper and lower pressure plates or rings 22. The pressure plates or rings 22 each have a slot portion 32 provided therein for facilitating bringing out low voltage lead 34 from the low voltage winding 21. The low voltage lead 34 is insulated from the respective core legs and from the pressure plates or rings 22 by means of insulators 36 and 36'. In core-form transformers of the type described it is necessary to provide pressure on the coils 20 to prevent movement of the coil sections 21 and 23 under short circuit conditions, which occur during short circuit testing of the transformer or which might occur after the transformer is placed in operation.

The pressure plates or rings 22 are made from laminated sheet metal. This metal has at least one preferred direction of orientation of the grain structure. In the arrangements illustrated herein the flux from the ends of the coils 20 travels in a direction perpendicular to the preferred direction of orientation of the grain structure of the laminated pressure rings 22.

FIG. 3 illustrates a plan or top view of a laminated pressure ring or plate 22 as used in this invention. The pressure ring or plate 22 is provided by selecting a strip of magnetic material having a preferred grain orientation in at least one direction and winding the strip material on a mandrel having approximately the same diameter as the diameter of the low voltage winding 22 until the outside diameter of the pressure ring 22 is substantially

the same as the outside diameter of the high voltage winding of coil 23. The strip of magnetic material may be either cold rolled grain oriented or hot rolled non-oriented, as desired. After the pressure ring 22 has been wound to the desired diameter, radial welds 38 are made at spaced intervals on both sides of the pressure ring to prevent the turns of the ring from uncoiling. Then the entire ring 22 is annealed to relieve any stresses locked in during the winding process. Before the strip material is wound to provide the ring a slight groove 50, as shown in FIG. 4, is provided in the strip material to prevent the strip material from telescoping as it is wound into a tight spiral. After the pressure ring 22 has been annealed to relieve locked in stresses an air gap 40 is cut completely across from the outside to the inside of the ring 22 to prevent the ring 22 from acting like a shorted turn. After the air gap 40 is cut across the ring the cut surfaces of the gap are etched to remove any burrs and the gap is filled with a thermosetting resinous material, such as epoxy resin. Epoxy resin is also brushed on both sides of the ring 22 to assist in holding the turns together to prevent splitting of the laminations.

The penetration of this resin is complete between adjacent laminations and the bond between adjacent laminations is stronger than the insulating film on the laminations after annealing. Several layers of insulating tape 42, such as polyester glass tape, may be wrapped around the circumference of the rings 22 to provide supplemental support to prevent the laminations of the rings 22 from splitting. This tape may be of glass epoxy or glass polyester or other high tensile strength tape.

Large core-form transformers having high reactance and high leakage flux have been made and tested incorporating laminated metallic pressure rings 22 such as described herein. The transformer losses when tested with the laminated metallic ring 22 were lower than in similar tests made with the transformer having no ring at all. When the same transformer was tested under the same conditions with a metallic ring 22 cut from a solid magnetic sheet, each ring 22 had several kilowatts of loss in it. Also it was found on the actual test of the transformer built and incorporating laminated metallic pressure rings 22 that under no circumstances did eddy currents cause the pressure ring 22 to heat up to a temperature high enough to scorch or otherwise damage the cellulosic insulation used to insulate the high and low voltage coils or windings 21 and 23. The test definitely showed that the laminated pressure rings 22 reduces the magnitude of the eddy currents and reduces losses in the transformer.

From the foregoing, it is seen that the present invention has provided a core-form transformer having high reactance and high leakage flux incorporating laminated

metallic pressure plates or rings which overcome many of the disadvantages of the solid steel type pressure plates or rings used in prior art transformers of this type.

While the present invention has been shown and described in only one form, it will be obvious to those skilled in the art that it is not so limited, but is susceptible of various changes and modifications without departing from the spirit thereof.

I claim as my invention:

- 10 1. A transformer comprising a magnetic core, said magnetic core having leg and yoke portions, first and second concentric windings surrounding a leg portion of said core, laminated metallic pressure rings between the ends of said windings and the yoke portions of said core, said pressure ring comprising a plurality of concentric turn laminations, each concentric lamination turn having at least one groove therein, said at least one groove in each lamination turn extending circumferentially of the lamination turn, said at least one groove in each lamination turn nesting with said at least one groove in an adjacent lamination turn to provide resistance to telescoping of said pressure ring when pressure is applied thereto, one of said pressure rings being located adjacent each end of said concentric windings, and means applying pressures 20 to each of said pressure rings to maintain said windings under pressure.
- 20 2. The transformer as claimed in claim 1 wherein an air gap is provided in each of said concentric laminations to prevent said pressure rings from acting like a shorted turn.
- 30 3. The transformer as claimed in claim 2 wherein each air gap in each said concentric turn lamination is substantially free of burrs which might cause shorting of the lamination turns to each other.
- 35 4. The transformer as claimed in claim 2 wherein each end of each concentric turn lamination is substantially free of burrs which might cause shorting of the lamination turns to each other.
- 40 5. The transformer as claimed in claim 3 wherein the air gaps are filled with a thermosetting resin.
